B. F. FAUNCE ET AL

STRIKING PLATE FOR CARS

Filed June 1, 1925

Fig. 5.

UNITED STATES PATENT OFFICE.

BENJAMIN F. FAUNCE, OF WESTMONT, AND HENRY C. DORRIS, OF JOHNSTOWN, PENNSYLVANIA, ASSIGNORS TO BETHLEHEM STEEL COMPANY.

STRIKING PLATE FOR CARS.

Application filed June 1, 1925. Serial No. 33,968.

Our invention relates to railway cars, and more particularly to the striking plate and is designed to cheapen and strengthen the end structure of the car against which the rear side of the draw bar head contacts to absorb the shocks and stresses and limit the return movement of the draw bar when the ends of cars are pushed together.

Heretofore it has been customary to make striking plates of cast metal, which required the making of a new mold for each casting. These castings are sometimes defective on account of blow holes, sand holes, or imperfect pouring, and have to be scrapped. Castings are also more or less rough when they are removed from the molds and have to be trimmed or finished in order to make a smooth surface where they are attached to the car and to remove any surplus metal from the sides or edges of the casting, all of which takes time and is expensive.

To obviate this difficulty of making castings and reduce the cost of production, we propose to make our striking plate of a flat rolled plate of metal, which is cut to the desired size and shape and then pressed into the required form between forging dies.

With this object in view, our invention consists in certain novel features of construction and combination, and arrangements of parts as hereinafter set forth and pointed out in the claims.

Having thus given a general description of our invention, we will now, in order to make the same more clear, refer to the accompanying sheet of drawings, in which like characters of reference indicate like parts.

Fig. 1 is a front elevation of our improved striking plate with enough of the end sill of the car to which it is attached to illustrate the application of our invention;

Fig. 2 is a top plan view of that portion of the end of a car shown in Fig. 1;

Fig. 3 is a sectional view taken on the line III—III of Fig. 2;

Fig. 4 is a front elevation of our improved striking plate detached;

Fig. 5 is a vertical sectional view of the striking plate taken on the line V—V of Fig. 4; and

Fig. 6 is a top plan view of the striking plate.

Referring to the drawings more in detail, 10 indicates the center or draft sill and 11 the end sill of the car. The striking plate

12 is secured to the central front face of the sill 11.

The striking plate 12 is of an inverted approximately U-shaped form and it is pressed or forged from a flat rolled plate 69 of metal. It has a vertical portion 13 and rivet holes 14 therein which register with rivet holes in the end sills for the rivets 15, by means of which the striking plate is attached to the end sill. 65

The striking plate 12 is further provided with an outwardly pressed abutment 16, against which the rear face 17 of the draw bar head engages to limit inward movement of the same. This abutment has inclined 70 end walls 18 and top and bottom walls 19 and 20. The plate is stiffened by depressing the metal to form channels 21 in the rear face thereof. The channels 21 open to and extend laterally from the recess that is 75 formed when depressing the metal to form the abutment 16. The channels 21 slope upwardly from the bottom of said recess to the normal plane of the plate and the walls thereof converge towards each other. By 80 this construction the plate is stiffened and the metal pressed up from the face constitutes a rigid reinforcement to the abutment member 16. 85

The striking plate is formed with extensions 22 at each side thereof that extend below the end sill with flanges 23 and 24 on their inner and lower edges, respectively, between which is a draw-bar opening 25 for the shank of the draw-bar. 26 indicates the 90 carry-iron having its ends riveted to the lower flange 24 of the side extension of the striking plate and its central portion upwardly offset upon which the shank of the draw-bar is adapted to be slidably supported. 95

The draft sills 10 are reinforced on their top ends by means of a tie plate 27 and between the same by a bent U-shaped plate 28, the central portion of which is in horizontal 100 alignment with the bottom wall 20 of the abutment 16.

It will be noted, by referring to the drawings, that our striking plate may be pressed up by one operation out of a single flat piece 105 of rolled plate, and that it may be easily and quickly attached to the end sill of a car.

While we have shown our invention in but one form, it will be obvious to those skilled in the art that it is not so limited, but is 110

susceptible of various other changes and modifications without departing from the spirit thereof, and we desire, therefore, that only such limitations shall be placed thereupon as are imposed by the prior art or as are specifically set forth in the appended claims.

Having thus described our invention what we claim as new and desire to secure by Letters Patent is:

1. A pressed steel striking plate for the end sill of a railway car comprising a horizontal body portion and a pair of integral laterally-extending leg portions, said body portion having an uninterrupted substantially rectangular recess dished in one face thereof and also having a laterally-disposed channel open to said recess and sloping from the bottom of said recess to the normal plane of the plate, said leg portions having flanges at their inner and bottom marginal edges which extend at right lines from the face of said leg portions in the general direction of said dished portion.
2. A pressed metal striking plate for the end sill of a railway car comprising a horizontal body portion and a pair of integral laterally extending leg portions, said body portion having an uninterrupted substantially rectangular recess dished in one face thereof and also having a laterally-disposed channel open to said recess and sloping from

the bottom of said recess to the normal plane of the plate, the side walls of said channel converging towards each other, said leg portions having flanges at their inner and bottom marginal edges which extend at right lines from the face of the leg portions in the general direction of said dished portion.

3. In combination, a pressed metal striking plate for the end sill of a railway car having a horizontal body portion and a pair of integral laterally-extending leg portions, said body portion having an uninterrupted substantially rectangular recess with inclined end walls dished in one face thereof and also having a laterally-disposed channel open to said recess and sloping from the bottom of said recess to the normal plane of the plate, said leg portions having flanges at their inner and bottom marginal edges which extend at right lines from the face of said leg portions in the general direction of said dished portion, and a bottom cross member having its terminal portions secured to the leg portions and its intermediate portion offset to fit therebetween.

In testimony whereof I hereunto affix my signature this 18th day of May, 1925.

BENJAMIN F. FAUNCE.

In testimony whereof I hereunto affix my signature this 18th day of May, 1925.

HENRY C. DORRIS.
